UNITED STATES PATENT OFFICE.

PERCY E. HUNTER, OF PITTSBURGH, PENNSYLVANIA.

ANNEALING-BOX.

1,321,043.

Specification of Letters Patent.

Patented Nov. 4, 1919.

Application filed April 15, 1918. Serial No. 228,789.

To all whom it may concern:

Be it known that I, PERCY E. HUNTER, a citizen of the United States, residing at Pittsburgh, in the county of Allegheny and State of Pennsylvania, have invented certain new and useful Improvements in Annealing-Boxes, of which the following is a specification.

My invention consists of an improvement 10 in annealing boxes adapted for the usual uses of such devices, and is particularly intended for use in annealing sheet metal used in the manufacture of tin plate.

In the use of such boxes, they are subjected to the severe action of continuous heat at high temperatures, and especially to the cutting or deteriorating action of the flames of the annealing oven. These conditions result in rapid destruction of any abrupt projecting portions of the box which may happen to be in the path of the gases of combustion, for which reason it is desirable to maintain over the entire several surfaces of the box, as plane and unvarying contours as 20 possible, avoiding any shoulders or projections which might be weakened or cut away by action of the fire. It is especially important to avoid any such features in connection with the main joints of the metallic 25 members of which the box is made, and the present invention is designed to provide a construction in which these objections are avoided, while maintaining a maximum strength, resistance to deterioration, rigidity, 30 and efficiency throughout the structure.

Generally stated, the improvement consists in providing the main body portion, *i. e.*, the sides and ends, of a continuous uninterrupted integral wall of uniform thickness, and a top portion connected therewith, in such a manner as to present a series of outer surfaces to the action of the oven heat, in the absence of any objectionable variations or projections.

45 The box is composed of two main blanks, one for the main side and end portions, and one for the top portion, as hereinafter described.

In the drawings, which show one preferred embodiment of the invention,

Figure 1 is a view in cross section of the side and end forming blank before welding, to form the joint about midway of one of the sides or ends;

Fig. 2 is a similar view after welding; 55

Fig. 3 is a detail view showing a modified arrangement, locating the welded joint adjacent to one of the corners, instead of at the middle of the side or end;

Fig. 4 is an enlarged view in vertical section and elevation, of the complete annealing box, indicated by the line IV—IV of Fig. 5;

Fig. 5 is a plan view of the complete box;

Fig. 6 is a sectional detail view of the 65 upper corner showing a riveted joint; and

Figs. 7, 8 and 9 are enlarged sectional detail views of the main wall, showing the steps of the welding operation in bringing the joint to finished shape. 70

In making the main body portion of the annealing box, I cut a blank of plate metal of suitable thickness and size so that when bent into form for use, it will approximate a rectangle having the back 2, ends 3, 3, 75 and the front composed of the end portions of the plate 4, 4, overlapping at 5, as shown in Fig. 1.

The overlap is of sufficient width, when these portions are adjusted, to insure ample 80 contacting area of the plates for a good welded joint. In order to provide ample stock for spreading outwardly of the meeting ends in making the joint, the ends 3 are, in the process of manufacture, brought 85 inwardly a sufficient distance so that when the material is stretched in making the weld, the ends will assume a position at right angles to the sides, as shown in Fig. 2. Thus, when completed, the box will be of 90 the form shown in Fig. 2 composed of the back 2, ends 3, 3, and continuous integral front 4—4^a. The corners are rounded, as shown, for good construction.

In welding the overlapping meeting ends 95 of the front portions 4, 4, they are brought together as in Fig. 7, and are then swaged down under a hammer, die, press, or other means, the meeting welded faces assuming a diagonal line *b* with the opposite corner 100 portions of the overlapping ends gradually merged into the general plane of the main front plate, inside and out, as at *c*, *c*, Fig. 8. The welding pressure is continued until the projecting portions are flattened into 105 the planes of the inner and outer surfaces, as in Fig. 9, by which operation the welded joint is increased, the rectangular symmetry

of the box is assumed, and the sides and ends are formed to compose a continuous substantially rectangular piece of homogeneous metal.

5 It is not, of course, absolutely essential that the exact planes of the inner and outer surfaces be approximated throughout, except at the inner upper flanged portion of the box, for continuous engagement of the 10 top.

The top 6 is made of a single piece of pressed plate metal having a middle upwardly arching dome portion and a surrounding outwardly extending attaching 15 edge portion 7. The top is of a suitable size to fit and bear by such edge portion inwardly against upper terminal inwardly turned edges 8 of the box, as in Fig. 4, when complete.

20 The inwardly turned upper edge portion of the main box is formed by suitable dies and pressing mechanism to provide the terminal retaining edge 8 which is bent inwardly, as shown, to give a good under bearing 25 seat for the corresponding upper face of the terminal edge portion of the top. The upwardly extending central dome portion of the top 6 extends outwardly and somewhat above such contacting portions, and 30 when located in position, the meeting edge portions are welded together all around and the parts are made practically integral. If preferred, the top may be flat.

If preferred, the edge 7^a of the top may 35 be riveted to the inwardly turned flange or edge 8^a of the box, as indicated in Fig. 6, either with or without the welding operation, thereby insuring a solid substantial joint. In each case, the top is fixedly 40 retained in position, and the parts being integral and substantially homogeneous when welded, form a continuous construction throughout.

By either construction, *i. e.*, either welded 45 or riveted, and with one side or end of the box welded in the manner described, I provide continuous, smooth, unobstructed surfaces at all points so that there is no opportunity for the flame of the annealing furnace to attack any projecting portion, thus 50 preventing wasting or weakening at any such points.

By bending over the top edge portion of the main box structure, providing a retaining flange, and by inserting the top from within so that its surrounding edge portion bears directly against such inwardly turned edge or flange, I avoid any outer projection and present a smooth, even surface with ample reinforcement and strength. Also, by such construction, because of the upwardly extending inner edge of the outer wall flanges, as shown, I provide a surrounding crevice or gutter 9 or 9^a adapted to be filled 55 with sand, clay or other suitable packing ma-

terial, as is commonly done for closing of leaks.

The box is provided with lifting lugs or buttons 10 at any suitable locations, preferably having shouldered and countersunk 70 riveted connection with the opposite sides of the box, as indicated at 11, thus facilitating easy and cheap renewal of these parts, when broken or worn.

In making the welded joint 4^a it is preferably located at a position between the corners, either at the side or end of the box. It may be made at the middle as in Figs. 1 and 2, or at one side of the middle, as in Fig. 3. With either construction I avoid joining the 80 side and end of the box at the corner, thereby preventing any weakening of the corner which thus maintains the original integral continuity of the plate. This is a feature of very considerable advantage over prior 85 constructions having corner joints of various kinds, which are subject to the weakening or destructive effect of the heat or other influences or strains resulting in failure of the box at such points.

90 The construction, operation, advantages and utility of the invention will be readily understood and appreciated by those accustomed to the use of annealing boxes of this general class. It is comparatively cheap and 95 simple in construction; durable and efficient in continued use because of the equal uniform construction throughout, and provides ample compensations for the usual strains and requirements of devices of this type.

100 What I claim is:—

1. An annealing box composed of a plate metal body portion having inwardly turned upper edges, and a top having a continuously integral middle body portion and a laterally 105 extending edge portion engaging underneath and secured to said upper edges.

2. An annealing box composed of a plate metal body portion having inwardly turned upper edges, and a top having a continuously integral middle body portion and a laterally 110 extending edge portion engaging underneath and secured to said upper edges, and providing an inner sand holding groove around the inner bottom portion of the inwardly turned upper edges.

3. An annealing box composed of a plate metal body portion having inwardly turned upper edges, and a top having an upwardly bowed middle portion and a laterally extending edge portion engaging underneath 120 said upper edges.

4. An annealing box composed of a plate metal body portion having inwardly turned upper edges, and a top having an upwardly bowed middle portion and a laterally extending edge portion engaging underneath 125 and secured to said upper edges.

5. An annealing box composed of a rectangular plate metal body portion formed 130

of a continuous blank having its ends overlapping and welded together by a swaged down overlapping joint substantially uniform with the normal thickness of the plate 5 and having a continuous surrounding similarly formed inwardly turned top flange portion of uniform thickness and continu- ously smooth under portion, and a top having a laterally extending edge portion engaging underneath and secured to the under 10 side of said top flange portion.

In testimony whereof I hereunto affix my signature.

PERCY E. HUNTER.
